7 Claims. (Cl. 114—240)

(Granted under Title 35, U.S. Code (1952), sec. 266)

This invention relates to a new and improved device for protecting a vessel against attacks by torpedoes and more particularly to devices comprising a plurality of explosive bombs arranged in spaced relation within the water about the vessel at a predetermined distance therefrom and adapted to be exploded selectively by signals received through the water from the approaching torpedo.

In devices of this general type heretofore proposed it has been the general practice to interpose a barrier between the oncoming torpedo and the vessel in which the torpedo is either destroyed or deflected from its course by moving into contact with the barrier. In certain other devices heretofore proposed the structure of the vessel includes a quantity of trapped air adjacent thereto adapted to reduce the force and effect of the explosion of the torpedo, one of the forms of devices of this type comprising an outer casing or "blister" secured to the hull of the vessel or formed integrally therewith below the water line within which the air is trapped.

These devices have not proved entirely satisfactory as a protection against the ravage of a modern torpedo for the reason that the rate of travel of the torpedo through the water and the destructiveness thereof have been greatly increased. Furthermore, these devices are cumbersome, expensive to install on a vessel and in certain cases require extensive changes in the hull of the vessel.

In the arrangement of the present invention a plurality of explosive filled containers or bombs are arranged about the vessel within the water at a predetermined distance therefrom, the bombs being preferably supported in the arranged position by a plurality of booms extending outwardly from the vessel. Respectively suspended from the end of each of the booms is a plurality of detecting devices arranged within the water adapted to receive a signal from the oncoming torpedo and thereby cause a firing circuit to be closed and explode one or more of the aforesaid bombs within the path of travel of the torpedo adjacent thereto as the torpedo moves into proximate spaced relation with the bomb. The explosion of the bomb causes the torpedo to be destroyed at a safe distance from the vessel or deflected from its course sufficiently to miss the target.

One of the objects of the present invention is the provision of a plurality of explosive charges arranged about a vessel adapted to destroy a torpedo while the torpedo is at a safe distance from the vessel in response to a signal received through the water from the torpedo.

Another of the objects is the provision of a plurality of torpedo detecting devices arranged about a vessel and secured thereto adapted to fire an explosive charge sufficiently near an oncoming torpedo to destroy the same.

Still another object is the provision of a plurality of groups of explosive charges arranged within the water about a vessel in spaced relation at a predetermined distance therefrom in which a selected group of the ex-

plosive charges is fired by a signal received through the water from the torpedo.

A still further object is the provision of a plurality of groups of explosive charges arranged in spaced relation within the water about a vessel at a predetermined distance therefrom in which the explosive charges of a selected group are fired in succession in response to a signal received through the water from an approaching torpedo.

Still other objects and advantages will be apparent from the following description taken in connection with the accompanying drawings of which:

Fig. 1 is a plan view of a vessel employing the device of the present invention in accordance with a preferred embodiment thereof;

Fig. 2 is a view in elevation taken along the line 2—2 of Fig. 1;

Fig. 3 shows an alternative arrangement of explosive charges suitable for protecting the vessel of Fig. 1;

Fig. 4 shows diagrammatically a circuit arrangement suitable for use with the system of Fig. 1;

Fig. 5 shows in diagrammatic form an arrangement of parts and circuits therefor suitable for use with the arrangement of Fig. 3;

Fig. 6 is a schematic diagram of the timing device of Fig. 5;

Fig. 7 is a circuit diagram showing a group arrangement of explosive charges suitable for use with the arrangement of Fig. 1 or 3;

Fig. 8 shows an alternative form of torpedo detecting means suitable for use with the arrangement of Fig. 2; and

Fig. 9 is a circuit diagram illustrating diagrammatically a firing system suitable for use with the system of Fig. 8.

Referring now to the drawings for a more complete understanding of the invention and more particularly to Figs. 1 and 2 thereof there is shown thereon a vessel indicated generally by the numeral 10 having a plurality of booms 11 pivotally secured thereto as at 12 and adapted

40 to be raised and lowered at will by the cables or lines 13 secured thereto and passing over the pulleys 14 and adapted to be controlled by winches 15. An arrangement is thus provided in which by operating the winches the booms may be raised to a substantially vertical position and lowered at will to the position shown on the drawings under control of the aforesaid winches. Where-

45 as in the illustrative embodiment of the invention each of the pulleys is provided with a winch individual thereto it will, of course, be understood that a multiple arrangement may be employed, if desired, whereby several of the booms may be raised and lowered at will by a single operation.

Each of the booms is provided with a pulley or sheave 16 rotatably secured thereto and adapted to pay out 55 a length of cable 17 therefrom having a microphone 18 connected to the cable conductors. There is also preferably connected to the microphone 18 in any suitable manner as by the member 19 a weight 21 thereby to insure that the cable 17 will be properly paid out

60 past the pulley 16 as the microphone and weight are lowered into the water. The cable 17 extends from the pulley 16 to the vessel in any suitable manner as by passing within the aforesaid boom or within a suitable guide secured thereto from whence the cable is continued past the pulleys 22 and 23 secured to the boom and to the vessel respectively and thence to an amplifier 24 arranged on the vessel.

There is also secured to each of the booms 11 a pulley 25 having a cable 26 passing thereover to which is connected an explosive bomb or charge 27 adapted to be lowered within the water at a depth preferably somewhat less than the draft of the vessel. The cable 26 is

connected at the opposite end thereof to a mine firing circuit comprising a source of electrical power and adapted to be closed by a firing relay or similar device in response to a signal received by the amplifier, Fig. 4, the connection between the amplifier and the firing circuit closing mechanism preferably including a filter device adapted to pass a signal within a predetermined frequency band characteristic of a torpedo being driven through the water by its propelling mechanism. Within each of the bombs 27 is arranged an electro-responsive detonating device adapted to be fired in response to the closure of the aforesaid firing circuit, as is well known in the art to which the present invention pertains.

On Fig. 3 is shown an alternative arrangement of bombs or explosive charges 28, 29 and 31 arranged on the boom 32 pivotally secured to the vessel 10 as at 33 and adapted to be raised and lowered by the cable 34 secured thereto. The bombs 28, 29 and 31 are respectively connected to and preferably supported by the cables 35, 36 and 37 passing over the pulleys 38 rotatably secured to the boom. The microphone or hydrophone 39 is connected to and supported by a cable 41 passing over the pulley 42 rotatably secured at the end of the boom 32, a weight 43 being preferably connected to the microphone as by the member 44 to facilitate the paying out of the cable 41 past the pulley 42 and to maintain the microphone at a predetermined depth of submersion within the water without substantial movement thereof.

The connection between the microphone and the explosive charges 28, 29 and 31 is illustrated diagrammatically on Fig. 5 on which the microphone is shown connected to the amplifier 24 by the cable 41, the output of the amplifier being connected to the filter F from whence the circuit is continued to the timing device T. The operation of the timing device T causes the firing circuit to be closed over the cables 35, 36 and 37 thereby to fire in quick succession the bombs 28, 29 and 31 respectively connected thereto.

The manner in which this is accomplished will be more clearly apparent by consideration of Fig. 6 on which is shown in diagrammatic form a timing device T suitable for use with the system of the present invention, the mechanism comprising, among other elements, a control relay C adapted to be operated by a signal received from the filter F. There is also included within the timing mechanism a distributor D having a rotatable brush 45 adapted to engage the contacts 46, 47 and 48 in rapid succession as the brush rotates and thereby establish a circuit from a source of potential at the feeder ring FR by way of the cables 35, 36 and 37 to the bombs 28, 29 and 31 whereby the bombs are fired in predetermined sequential order as the brush 45 traverses the contacts 46, 47 and 48 of the distributor D. The brush 45 is secured to a rotatable shaft 49 operatively connected preferably by a friction clutch 51 and gear box 52 to a motor M. Relay C, it will be noted, is provided with an armature 53 adapted to engage a contact 54 and apply potential to the motor M as the relay operates in response to a signal received from the filter F. The operation of relay C at the armature 55 thereof also applies battery by way of conductor 56 to the distributor start magnet SM and causes the start magnet to be energized and attract the latch 57 thereby releasing the brush 45 and setting the distributor in operation to fire the explosive charges within the bombs 28, 29 and 31. Relay C is preferably adapted to move the armature 53 thereof into engagement with the make contact 54 slightly in advance of the engagement of armature 55 thereof with the associated make contact whereby the motor M is brought up to speed before the start magnet SM is operated.

An arrangement is thus provided in which the brush 45, when released by the start magnet SM, invariably operates at a predetermined speed of rotation and the interval of time between the reception of the under water signal by the associated microphone 43 and the explosion of

the bombs 28, 29 and 31 is fixed such that the bombs are exploded in predetermined time spaced relation during the movement of the torpedo adjacent thereto.

On Fig. 7 is shown in diagrammatic form a plurality of microphones M and bombs B adapted to be suspended from a plurality of booms generally in the manner of Fig. 1, in which the same subscripts are employed to designate the microphone and bomb suspended from the same boom and in which the bombs comprising a selected group are adapted to be exploded substantially simultaneously in response to a signal received from one or more of the microphones. For the purpose of description six bombs, B, B1, B2, B3, B4 and B5 are shown operatively connected in groups to the microphones M1 to M5 although it will, of course, be understood that the arrangement disclosed may be extended to include as many microphones and bombs as may be desired. Respectively associated with each of the microphones is an amplifier 24 having a filter F connected to the output thereof adapted to pass a signal having a frequency characteristic of the signal produced within the water by an oncoming torpedo. The output of each of the filters is connected respectively to a plurality of firing relays FR1 to FR5, each of the firing relays being provided with means such, for example, as a copper slug or sleeve arranged about the core thereof to render the relay slow operating and thereby provide sufficient time for the torpedo to travel within the destructive range of the bombs controlled thereby before the bombs are fired by the firing relay.

Let it be assumed, by way of example, that the microphone M1 is arranged at a particular portion of the vessel 10 such, for example, as the bow. The operation of relay FR1 in response to a firing signal received from the microphone M1 closes a firing circuit from the armatures 58 thereof to the bombs B, B1 and B2, the bomb B1 being supported by the boom associated with the microphone M1 and the bombs B and B2 being supported by booms respectively disposed on opposite sides of the boom supporting the bomb B1 and microphone M1.

In like manner the operation of relay FR2 causes the bombs B1, B2 and B3 to be simultaneously exploded as the relay contacts are closed in response to a signal received from the microphone M2, relay FR3 is adapted to explode bombs B2, B3 and B4, relay FR4 to explode bombs B3, B4, B5 and relay FR5 to explode bombs B4, B5 and B6 (not shown), sufficient additional explosive devices and control means therefor being provided to extend the zone of protection completely about the vessel. Whereas on Fig. 7 is shown an arrangement in which each of the firing relays is adapted to explode the bombs supported by booms on opposite sides of the bomb associated with the microphone controlling the firing relay, it will be understood that this has been done for the purpose of description and that various other combinations and arrangements may be effected within the scope of the invention such, for example, as the arrangement of Fig. 3 in which more than one bomb is disposed on each boom. By arranging the bombs in groups in the manner disclosed herein, the firing power and effective destructive area of the explosion is increased with a corresponding decrease in the possibility that a torpedo may approach the vessel from such an angle as to escape premature destruction before reaching the target.

An alternative form of the torpedo detecting device is disclosed on Fig. 8 in which the presence of the torpedo is made manifest by an electrical potential received at the pair of insulated electrodes 59 from the electric field set up within the water by the oncoming torpedo. The electrodes are composed of material suitable for the purpose such, for example, as silver chloride and maintained in predetermined space relationship with respect to each other within the water by the member 61 to which the electrodes are connected, suitable means being provided to prevent an electrical connection therebetween except such connection as may be established through

the surrounding sea water. The electrodes 59 are respectively connected to and supported by a pair of cables or conductors 62 passing over a pair of pulleys 63 rotatably secured to the boom 64 whereby the electrodes are arranged within the water in such a manner as to cause a potential to be set up across the conductors 62 by the electric field of the torpedo when the torpedo has approached within a predetermined distance of the electrodes.

When this occurs, the amplifier 65, Fig. 9, is caused to send an output signal sufficient to operate the slow operating firing relay 66 in time delayed relation with respect to the closure of the operating circuit thereto. As armature 67 of relay 66 moves into engagement with its make contact a circuit is closed from the positive terminal of battery BA by way of conductor 68, armature 67 and make contact of relay 66, conductor 69 within cable 71 and thence to the detonator within the bomb 72 from whence the circuit is continued by way of conductor 73 within the cable 71 to the negative terminal of battery BA thereby causing the detonator to operate and fire the bomb 72 adjacent the torpedo.

Whereas in the foregoing description the bombs have been suspended directly from a plurality of booms extending outwardly from the vessel, it will, of course, be understood that, if desired, the bombs may be arranged from a chain or cable extending from each boom to the adjacent booms and, furthermore, the bombs and detecting elements may, if desired, be combined into a unitary structure. Each of the microphones employed with the present invention is arranged to have a field of detection sufficiently large to overlap the field of detection of the adjacent microphones and thus, in the event that a torpedo should pass substantially midway between two adjacent microphones the signal generated by the torpedo would be effective to operate both microphones to explode the bombs controlled thereby. Furthermore, if desired, the pair of electrodes 59 may be connected to one arm of a Wheatstone bridge having the firing relay included within the galvanometer circuit thereof and adapted to be operated when the resistance of the leg of the bridge is varied by the presence of a torpedo within the vicinity of the electrodes.

While the invention has been described with reference to several examples thereof which give satisfactory results, it will be understood by those skilled in the art, after understanding the invention, that various changes and modifications may be made without departing from the spirit and scope of the invention and it is my intention, therefore, in the appended claims to cover all such changes and modifications.

The invention herein described and claimed may be manufactured and used by and for the Government of the United States of America for governmental purposes without payment of any royalties thereon or therefor.

What is claimed as new and desired to be secured by Letters Patent of the United States is:

1. A vessel protector comprising a plurality of elongated mounting means adapted for attachment to the exterior of the vessel and projecting laterally therefrom, a plurality of explosive bombs arranged within the water at a distance from the vessel and respectively supported by said mounting means, a plurality of signal detecting devices arranged within the water and supported by each of said mounting means at the free end thereof, a plurality of means for amplifying the signals received by said signal detecting devices, a plurality of firing relays respectively controlled by said signal amplifiers each adapted to close a plurality of contacts as the relay operates, and a plurality of firing circuits adapted to be closed by said contacts and explode a selected group of said explosive bombs.

2. In a device of the character disclosed for protecting a vessel against attack by a marine torpedo, the combination of a plurality of signal detecting devices arranged

about the vessel within the water, a plurality of explosive charges arranged within the water intermediate said detecting devices and the vessel, a plurality of signal amplifying devices associated with each of said detecting devices respectively and controlled thereby, each of said amplifying devices having a filter mechanism connected thereto adapted to pass a signal of predetermined character corresponding to a signal received from the oncoming torpedo by said detecting devices, and means including a plurality of firing relays respectively connected to said signal amplifying devices for firing said explosive bombs in groups selectively in accordance with signals received by said detecting devices.

3. In a torpedo guard for a vessel, the combination of a plurality of explosive charges arranged in serial order within the water about the vessel, a plurality of microphonic detecting devices arranged about the vessel beyond said explosive charges thereby to establish a continuous zone of detection about the vessel, means for firing said explosive charges, and means controlled by signals received from said detecting devices as the torpedo moves into said zone of detection for operating said firing means in sufficient time delayed relation with respect to the signal received by the detecting devices to cause at least one explosive charge to be fired adjacent said torpedo.

4. In a system of the character disclosed for protecting a vessel from attack by a marine torpedo, the combination of a plurality of microphonic detecting devices arranged about the vessel within the water in spaced relation such that a portion of the field of detection of at least one of the detecting devices overlaps the zone of detection of the adjacent detecting devices, a plurality of explosive charges arranged about the vessel intermediate said detecting devices and the vessel, means for firing a predetermined number of explosive charges substantially within the path of travel of the oncoming torpedo in response to a signal received by one of said detecting devices as the torpedo moves within the detecting zone thereof, and means for firing a substantially greater number of explosive charges adjacent the path of the torpedo when the torpedo has moved within an overlapping portion of said zone of detection.

5. In means for destroying a marine torpedo as it approaches a vessel, the combination with the vessel of a series of outwardly projecting booms, a plurality of signal detecting devices arranged within the water and supported by the booms at the free end portions thereof, a plurality of explosive bombs arranged within the water supported by said booms, and means controlled by said detecting devices for firing in succession a predetermined group of said bombs selectively in response to a signal received through the water by said detecting devices from said torpedo.

6. In a device for destroying a marine torpedo as it approaches a vessel, the combination with the vessel of a series of outwardly projecting booms, a plurality of signal detecting devices arranged within the water and supported by the booms at the free end portions thereof, a plurality of explosive bombs arranged within the water and supported by said booms, a plurality of signal amplifiers respectively connected to said signal detecting devices, a plurality of timing devices operatively connected to each of said signal amplifiers respectively and adapted to be controlled thereby, each of said timing devices having means to close a plurality of electrical circuits in predetermined order in quick succession as the device operates, and means for causing the bombs of a selected group to be fired in succession as said circuits are closed.

7. In a device for destroying a marine torpedo as it approaches a vessel, in combination with the vessel, a series of outwardly projecting booms, a plurality of signal detecting devices arranged within the water and supported by the booms, a plurality of explosive bombs arranged in groups within the water and supported by said

booms intermediate the detecting devices and the vessel, a plurality of normally inactive timing devices operatively connected to each of said detecting devices respectively, each of said timing devices having a rotatable member adapted to close a plurality of contacts in quick succession as the device operates, means responsive to a signal of predetermined character received from an oncoming torpedo by one of said signal detecting devices for setting the respective timing device in operation, and means including a plurality of firing circuits 10 for firing the bombs of a selected group adjacent the

moving torpedo in quick succession as said plurality of contacts are closed by said rotatable member.
